SIGURD STRUNGE, OF WYANDOTTE, MICHIGAN.

FRICTION SCREW-LIFTING MECHANISM.

Application filed April 17, 1926. Serial No. 102 645.

This invention relates to lifting mechanism and the like, and more particularly to such mechanism operating by rollers engaging an unthreaded surface, wherein friction alone is utilized for advancing the members to be lifted, thereby rendering unnecessary the use of interengaging screw threaded members for such purposes.

It has long been a desideratum among engineers, contractors and others to employ satisfactory unthreaded lifting mechanism in lifting comparatively heavy members such, for example, as the molds utilized in building concrete walls, piers, etc. Where the walls, etc. are of comparatively great height the provision of threaded poles for carrying the molds and lifting apparatus is quite expensive, and the transportation of such poles from one job to another is difficult and hazardous. One object of my invention is the provision of apparatus for lifting comparatively heavy members by the use of unthreaded poles and unthreaded cylinders engaging therewith.

Another object of my invention is the arrangement of a plurality of friction rollers within a turnable frame and adapted to engage an unthreaded pole or shaft so that when the frame is rotated in one direction the rollers will spirally advance upon the pole or shaft.

A further object of my invention is the provision of a friction roller having a curved periphery shaped so that it may engage the surface of a shaft or pole in a plurality of points, with means for mounting such roller and maintaining it in contact with the shaft.

Other objects and advantages will be apparent from the following description, wherein reference is made to the accompanying drawings illustrating a preferred embodiment of my invention and wherein similar reference numerals designate similar parts throughout the several views.

In the drawings:

Fig. 1 is a plan view of my improved lifting mechanism mounted upon a frame carrying molds adaptable for use in building concrete walls.

Fig. 2 is a side elevation thereof.

Fig. 3 is an enlarged vertical sectional view, taken substantially on the line 3—3 of Fig. 1.

Fig. 4 is a detail cross section taken substantially on the line 4—4 of Fig. 3.

Fig. 5 is a detail perspective view of the support member for the lower extremities of the friction rollers.

Fig. 6 is a detail elevation of the means for adjusting the position of the member supporting the upper extremities of the friction rollers, and

Fig. 7 is a detail section taken substantially on the line 7—7 of Fig. 3.

Referring now to the drawings, the numeral 5 designates an electric motor or other suitable source of power adapted to rotate the shaft 6 carrying a worm gear 7 or the like arranged to mesh with a worm pinion 8 fixed upon the periphery of the barrel or frame 9 in which my friction rollers 10 are carried. The rollers 10 are shaped with their peripheries concave to a slight extent, and are mounted within the barrel 9 on shafts 11 arranged at an angle to the vertical axis 73 of the barrel, substantially as shown in Figs. 3 and 4. The longitudinal axes of the shafts 11 are arranged in planes intersecting each other and both intersecting the vertical plane of a supporting pole or shaft 12 extending substantially centrally through the barrel 9 between the rollers 10. The lower extremities of the shafts 11 are mounted within apertures 13 in a bottom plate 14 adapted to be secured within the barrel 9, as by screws 15 or other fastening means, and the rollers 10 are arranged to rotate freely upon the shafts 11, as by suitable antifriction ball bearings 16 adjacent each extremity of the rollers 10 (note Figs. 3 and 7). The upper 90 extremities of the shafts 11 pass through apertures 17 in a top plate 18 arranged within the barrel 9 adjacent its upper extremity. The top plate 18 rests upon the upper roller bearings of the cylinders 10, and is adjustably mounted within the barrel 9 so as to permit rotation of the top plate 18 relatively to the barrel. The particular means of adjustment herein disclosed for the movement of the top plate 18 is best shown in Figs. 1 and 6. The barrel 9 is formed adjacent its upper extremity with a bayonet slot 19 and the top plate 18 is formed with a radially projecting lug 20 adapted to enter and be seated within the bayonet slot 19. One face of the lug 20 is shaped for engagement by an adjusting bolt 21 threaded within an ear 22 fixed upon the barrel 9 in horizontal alignment with the lower portion of the bayonet slot 19 (note Fig. 6). In prac- 105 110

tice, the lug 20 of the top plate is passed through the vertical upper portion of the bayonet slot 19 and then swung into the horizontal lower portion of the bayonet slot beneath the upper wall of the bayonet slot. This serves to prevent accidental dislocation of the top plate 18 while the apparatus is in use, and also provides means for swinging the upper portion of the shafts 11 and rollers 10 to provide means to seat the rollers against the surface of the shaft 12 with various pressures. The turning of the adjusting bolt 21 in the proper direction will force the lug 20 further into the horizontal portion of the bayonet slot 19 and so swing the upper portions of the shafts 11 and rollers 10.

By virtue of this construction a pole or shaft 12 can be fixed in any desired position, as for example vertically, and the rollers 10 then brought into frictional contact therewith, substantially as shown in Figs. 3 and 4, whereupon the turning of the barrel 9 in the proper direction will cause the rollers 10 to climb upon the shaft or pole 12. The upward movement of the rollers 10 will continue as long as the rotation of the barrel 9 is continued, and the advance upon the shaft 12 is contingent upon the arrangement of the rollers relatively to the shaft as well as upon the degree of concavity of the peripheries of the rollers 10. It is preferred that the arrangement of the rollers as well as the degree of curvature of their peripheries be such that the advance movement of the rollers upon the shaft 12 is relatively small, as for example, a fractional part of an inch to each revolution of the barrel 9. The frictional contact of the rollers upon the pole 12 will prevent the accidental downward movement of the barrel 9 and attached portions when the rotation of the barrel has ceased; but it will be apparent that the barrel and attached parts can be again lowered by reversing the rotation of the barrel whenever desired. I prefer to mount the motor 5 or other source of power for rotating the barrel 9 upon a framework moyable with the barrel. In the illustrated embodiment I have shown the motor 5 mounted on the upper deck 23 of a framework 24 supporting a pair of molds 25 suitable for use in building concrete walls and the like. As best shown in Fig. 2 the molds 25 are formed with vertical portions separated from each other by the width of the wall to be built and held in such positions by means of horizontal portions 25^a on the molds as well as by brace blocks 26 fixed between the outer walls of the vertical portions of the molds and the lower portions of the framework 24. Tie rods 27 may be suitably arranged between the blocks 26 and a sleeve 28 surrounding and resting upon a depending collared member carried by the bottom plate 14 of the barrel 9, whereby the weight of the

molds 25, framework 24 and motor 5 are directly carried by the barrel 9. The collared portion 29 has a central vertical opening of greater area than the diameter of the pole 12 and is preferably secured to a collar 30 upon the bottom plate 14 of the barrel 9 (note Fig. 3). The collared portion 29 rotates with the barrel 9 within the sleeve 28, and the lower extremity of the sleeve 28 rests upon a ball bearing 31 carried upon the upper surface of the base of the collared portion 29, substantially as shown in Fig. 2.

In practice the molds 25 are set for the first pouring of concrete, and then after this pouring has sufficiently set, the molds 25 are lifted to the position desired for the next pouring by the rotation of the barrel 9 by means of the motor 5. The rotation of the barrel enables the rollers 10 to climb upon the shaft 12 and pull with them the framework 24 and molds 25, as above recited. When the desired new position of the molds has been reached the motor 5 is stopped and the next pouring of concrete made. The operation is repeated as often as desired. The shaft 12 can be buried within the concrete poured, if desired.

From the above it will be obvious that lifting means for comparatively heavy members, such as concrete molds, is provided which do not necessitate the use of threaded poles or shafts, but instead poles or shafts having smooth or slightly roughened surfaces can be utilized.

It will further be obvious that a plurality of my improved lifting mechanisms can be operated in unison, as for lifting molds of comparatively great length, such as are used in building concrete piers, etc.

While it will be apparent that the illustrated embodiment of my invention herein disclosed is well calculated to adequately fulfill the objects and advantages primarily stated, it is to be understood that the invention is susceptible to variation, modification and change within the spirit and scope of the subjoined claims.

Having described my invention, I claim:

1. Lifting mechanism comprising a pole, a plurality of angularly arranged friction rollers engaging the periphery of the pole, a frame encircling the pole and carrying the rollers, and means for rotating the frame.

2. Lifting mechanism comprising a pole, a plurality of angularly arranged friction rollers engaging the periphery of the pole, a frame encircling the pole and carrying the rollers, means for rotating the frame and rollers, and means for adjusting the pressure of contact of the rollers upon the pole.

3. Lifting mechanism comprising a pole, a plurality of angularly arranged friction rollers engaging the periphery of the pole, a frame encircling the pole and carrying the rollers, and means for rotating the frame, the

rollers being arranged in intersecting planes and rotatable with the frame.

4. Lifting mechanism comprising a pole, a plurality of angularly arranged friction rollers engaging the periphery of the pole, a frame carrying the rollers having a fixed bottom plate and a movable top plate through which the shafts of the rollers project, means for adjusting the position of the top plate to 10 vary the pressure of contact of the rollers upon the pole, and means for rotating the frame.

5. Lifting mechanism comprising a pole, a plurality of angularly arranged friction 15 rollers engaging the periphery of the pole, a frame carrying the rollers, and means for rotating the frame, comprising a worm pinion fixed upon the frame, a worm gear meshing with the pinion, and means for rotating 20 the worm gear.

6. Lifting mechanism comprising a shaft, a frame surrounding the shaft, a plurality of friction rollers engaging the periphery of the shaft and journaled in the frame, said 25 rollers having concave peripheries and being angularly disposed in intersecting planes, and means for rotating the frame to advance and recede the rollers and frame upon the shaft.

7. Lifting mechanism comprising a shaft, a plurality of angularly arranged friction 30 rollers engaging the periphery of the shaft, a frame surrounding the shaft and carrying said rollers, said rollers having concave peripheries and being angularly disposed in intersecting planes, means for rotating the frame to advance and recede the rollers and frame upon the shaft, and a collared portion carried by the frame and adapted to support 35 the members to be lifted.

8. Lifting mechanism comprising a shaft, a plurality of angularly arranged friction rollers engaging the periphery of the shaft, a frame surrounding the shaft and carrying said rollers, said rollers having concave peripheries and being angularly disposed in intersecting planes, means for rotating the frame to advance and recede the rollers and frame upon the shaft, a collared portion depending from the frame, and a sleeve encircling 45 and resting upon the collared portion, whereby the members to be lifted are secured upon the frame.

9. Lifting mechanism comprising a shaft, a plurality of angularly arranged friction 50 rollers engaging the periphery of the shaft, a frame surrounding the shaft and carrying said rollers, said rollers having concave peripheries and being angularly disposed in intersecting planes, means for rotating the 55 frame to advance and recede the rollers and frame upon the shaft, a collared portion depending from the frame, a sleeve encircling and resting upon the collared portion, and a framework depending from said sleeve. 60

10. Lifting mechanism comprising a pole, a barrel loosely surrounding the pole, a pair of stub shafts angularly disposed within the barrel, concave rollers journaled upon the stub shafts and contacting the periphery of 65 the pole, means for varying the pressure of contact of the rollers upon the pole including a turntable top plate within the barrel and having a lug projecting through a slot in the barrel, an adjusting bolt mounted upon the 70 barrel for engagement with the lug, the barrel having a bayonet slot with its longer portion in alignment with the adjusting bolt. 75

In witness whereof I hereunto set my hand.
SIGURD STRUNGE.
